Primary Examiner — R. Johnson

(57) **CLAIM**

The ornamental design for an electronic piano as shown and described.

DESCRIPTION

FIG. 1 is a perspective view of electronic piano showing the new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the portion taken at line-9 in FIG. 1; and,

FIG. 10 is an enlarged view of the portion taken at line-10 in FIG. 2.

In the drawings, the dot-dashed broken lines illustrate the enlarged portions of the designs.

1 Claim, 10 Drawing Sheets
